A. KUBIAK,
CURTAIN HANGER,
APPLICATION FILED FEB. 19, 1921.

1,414,289.

Patented Apr. 25, 1922.

UNITED STATES PATENT OFFICE.

ANTONI KUBIAK, OF PATERSON, NEW JERSEY.

CURTAIN HANGER.

1,414,289.

Specification of Letters Patent. Patented Apr. 25, 1922.

Application filed February 19, 1921. Serial No. 446,413.

To all whom it may concern:

Be it known that I, ANTONI KUBIAK, a citizen of Poland, residing at Paterson, county of Essex, and State of New Jersey, have invented certain new and useful Improvements in Curtain Hangers, of which the following is a specification.

This invention relates to improvements in adjustable curtain poles, and it is the 10 principal object of the invention to provide a simple, neat and efficient pole of this type which is adapted to fit window and other frames of different widths, without requiring any special fasteners to secure it in position.

15 Another object of the invention is to provide a curtain pole which can be extended or contracted to any desired degree, and which is adapted to hold curtains of different widths.

20 A further object of the invention is to provide an adjustable curtain pole allowing a ready separation of the telescoping parts thereof for facilitating the adjustment of the curtain.

25 In the accompanying drawing I have disclosed the preferred embodiment of my invention and have described the same in detail hereinafter, but as the invention is susceptible of various modifications, the form 30 which is shown in the drawing is to be considered as illustrative, rather than restrictive of the scope of my invention.

In the accompanying drawing—

35 Figure 1 is a front view of the curtain pole constructed according to the present invention attached to a window frame, and

Figure 2 is a detail top plan view of one of the telescoping members of my pole detached from the other member.

40 Figure 3 is a detail sectional view illustrating the engagement between the head of the spring and one of the telescoping members.

45 Referring to the drawing, the curtain pole consists of the two telescoping parts or members 10 and 11, which are both hollow for the reception of a strong spiral spring 12, secured with one of its ends to a pin 13 within the member 11, while its other end is

50 straightened to form a part 14 ending in a head 15 adapted to be passed through a suit-

able opening 16 in the member 10, which opening ends in a restricted part 17 so that under the tension of the spring, the head 15 is held against the outer wall of the member 55 10, while the part 14 extends through the restricted part 17 of the opening 16.

At their outer ends both members 10 and 11 carry brackets 18 and 19, provided with 60 teeth or spikes 20 and 21 respectively, with which the same engage the outer edges of the wood work of a window frame 22.

In operation the head 15 is pulled in one direction so that it can be passed through the 65 opening 16, and the telescoping parts 10 and 11 are disengaged allowing a curtain to be drawn over the member 10, thereafter the parts or members 10 and 11 are united again the part 14 is bent as indicated in Figure 3 70 and the head 15 is pulled through the opening 16 and engages under the pull of the spring 12, the outer wall of the member 10, at the restricted part 17 of the opening 16.

Then the pole is extended to fit with its 75 bracket teeth against the outer edge of a window or the like frame and the spring will draw the teeth 20 and 21 into the wood work of the frame to hold pole and curtain in their adjusted relative positions.

Having thus described my invention, what I claim is:

In a curtain pole of the class described, a pair of hollow telescoping members, a spring within said members, a pin within one of 85 said members to which one end of said spring is fixedly secured, the other member having a slot ending in a restricted part, a head on the free end of said spring adapted to be drawn through the opening in said last 90 named member to engage the outer wall thereof at the restricted part of said slot, a pair of brackets at the ends of said members, and teeth on said brackets adapted to be drawn into the wood work of a window 95 frame by the action of said spring for securing the pole to windows of different widths while accommodating curtains of a corresponding width.

In testimony whereof I have affixed my 100 signature.

ANTONI KUBIAK.
